UNITED STATES PATENT OFFICE.

ANTONIUS C. ALBRECHT, OF PHILADELPHIA, PENNSYLVANIA.

ICE-CREAM FREEZER.

SPECIFICATION forming part of Letters Patent No. 239,212, dated March 22, 1881.

Application filed February 17, 1881. (No model.)

To all whom it may concern:

Be it known that I, ANTONIUS C. ALBRECHT, a citizen of the United States, residing in Philadelphia, Pennsylvania, have invented 5 certain Improvements in Ice-Cream Freezers, of which the following is a specification.

The object of my invention is to make a cheap ice-cream freezer for family use, an object attained by the adoption of simple and inexpensive parts, and modes of construction too fully described and claimed hereinafter to need preliminary explanation.

In the accompanying drawings, Figure 1 is a vertical section of an ice-cream freezer with 15 my improvements; Fig. 2, a sectional plan on the line 1 2, part of the cover of the can being removed to show the scraper; Fig. 3, an inverted plan view of the cross-bar; Fig. 4, a transverse section on the line 3 4, Fig. 3; Fig. 20 5, a vertical section of the cover of the can; Fig. 6, a perspective view of the upper portion of the freezer, part of the cross-bar being cut away to show the gearing; and Figs. 7 and 8, perspective views, showing the manner of connecting the wooden scraper to the arms of the dasher.

The outer vessel, A, of the freezer, as shown in the present instance, is made of wood, but may be of sheet-iron galvanized, and to the top 30 of this vessel is adapted the detachable cross-bar B in the following manner: This cross-bar, which is made of cast-iron, has at one end a hook, a, which can, on raising the opposite end of the cross-bar, be introduced into a slot in 35 a cleat, b, secured to the outer vessel, said opposite end of the cross-bar having an opening, d, for admitting the upper end, e, of the plate D, which is secured to the said outer vessel, A. When the cross-bar is in place it may be read- 40 ily secured by a turn-buckle, E, which is pivoted to the bar, and on which is a segmental inclined plane, f, so that on moving the turn-buckle in the direction of the arrow, Fig. 6, the inclined plane, bearing against the under side 45 of a shoulder on the end e of the plate D, will bind the cross-bar tightly to the upper edge of the outer vessel, A, the turn-buckle being so formed that when it is moved in a direction contrary to that pointed out by the arrow it 50 will be clear of the said shoulder, and the cross-

bar will be at liberty to be first elevated at one end and then detached from the cleat b.

The cream-can F has at the bottom the usual central pivot adapted to a step, i, secured to the bottom of the can itself is a recess for receiving the lower pointed end, h, of the dasher-spindle G, the upper square end of which fits loosely in a square opening, j, in the cross-bar B. The usual inclined arms k project from the dasher-spindle, the latter being also provided with arms m m', to which the wooden scraper H is connected in the peculiar manner described hereinafter.

A cast-iron lid, I, is fitted snugly to, but so 65 as to be easily removed from, the upper end of the cream-can, a stop, p, on the former being brought into contact with a projection, n, on the latter, so that the cover cannot turn independently of the can. A cog-wheel, J, is secured to the cover I, between which and the wheel is an annular recess, q, so that the said wheel becomes an available handle by which the said cover may be withdrawn from, and re-adjusted to, the cream-can.

A wheel, K, having teeth adapted to those of the wheel J, is secured to a spindle, t, having two bearings, one in the cross-bar B and the other in a bracket, w, secured to the under side of the cross-bar, above which the spindle is 80 provided with a suitable handle, M.

It will be seen that the wheel K and its spindle are carried by the cross-bar, so that on removing the latter the cream-can will be at liberty, the wheel K coming into gear with 85 the wheel J of the can when the cross-bar is readjusted to its place.

It may here be stated that the easiest way of making the cover is to first cast the wheel and its hub, and then to introduce a portion 90 of the latter into the mold prepared for casting the cover I.

The peculiar manner of connecting the scraper H to the arms m m' of the dasher is shown in the perspective views, Figs. 7 and 8. The 95 lower arm, m, has in the under side a recess for receiving a pivot, u, on a small casting, N, having two wings, the lower end of the scraper H being introduced between these wings, after which the latter are compressed by a suitable 100

instrument, and are thus made to gripe the scraper. A similar casting, N', is similarly attached to the upper end of the scraper, and a pivot, u', on this casting is adapted to a recess in the upper arm, m', of the dasher.

In applying the scraper to the arms the casting N' is first secured to the said scraper, and its pivot adjusted to the recess of the arm m', after which the pivot of the casting N is adjusted to the recess of the arm m, and its wings subsequently gripe to the scraper, or the lower casting may be first griped to the scraper and its pivot adjusted to the recess of the arm m, after which the pivot of the casting N' is adjusted to the recess of the arm m', and its wings subsequently griped to the scraper, which in either case is thus pivoted to the dasher without any of the usual pins or rivets.

A very cheap ice-cream freezer may be made 20 in the manner above described, the parts being few in number, easily and economically made, and readily put together, and affording means for the ready adjusting of the can within, and its withdrawal from, the outer vessel.

25 The manner of operating the freezer for the purpose of freezing the cream by the rotation of the cream-can in contact with ice contained between it and the outer vessel will be readily understood without explanation.

30 I claim as my invention—

1. The combination, in an ice-cream freezer, of the vessel A, having a cleat, b, and plate D, with the cross-bar B, adapted at one end to the cleat, and carrying near the opposite end a

turn-buckle, E, having a segmental inclined 35 plane, f, adapted to a shoulder on the upper projecting end, e, of the said plate D, all substantially as described.

2. The combination, in an ice-cream freezer, of the cream-can F, and its cover I, having a 40 cog-wheel, J, with the outer vessel, A, and its detachable cover B, carrying the spindle t and cog-wheel K, all substantially as specified.

3. The combination of the cross-bar B and bracket w, secured to the same, with the wheel 45 K and its spindle t, having one bearing in the cross-bar above the wheel and another bearing in the bracket below the wheel, as set forth.

4. The combination of the dasher-spindle G, the cream-vessel, having a cover, I, adapted to 50 turn on the said spindle, and having a cog-wheel, J, and the outer vessel, having a detachable cross-bar, B, carrying the spindle t and wheel K, and having an opening for receiving the end of the dasher-spindle and preventing 55 the turning of the same, all as described.

5. The combination of the dasher and its recessed arms m m' with the scraper H, and castings N N' each having a pivot and two wings 60 for embracing the scraper, as set forth.

In testimony whereof I have signed my name to this specification in the presence of two subscribing witnesses.

ANTONIUS C. ALBRECHT.
